(57) **CLAIM**

The ornamental design for a card reader, as shown and described.

DESCRIPTION

This application is related to U.S. patent application Ser. No. 16/364,297, filed Mar. 26, 2019, the entire disclosure of which is hereby incorporated herein by reference.

This application is related to U.S. patent application Ser. No. 16/364,314, filed Mar. 26, 2019, the entire disclosure of which is hereby incorporated herein by reference.

This application is related to U.S. patent application Ser. No. 16/364,327, filed Mar. 26, 2019, the entire disclosure of which is hereby incorporated herein by reference.

FIG. 1 is a perspective view of a card reader showing our new design in a first orientation;

FIG. 2 is another perspective view thereof;

FIG. 3 is a top plan view thereof;

FIG. 4 is a bottom plan view thereof;

FIG. 5 is front elevational view thereof;

FIG. 6 is a rear elevational view thereof;

FIG. 7 is a left side elevational view thereof;

FIG. 8 is a right side elevational view thereof;

FIG. 9 is a view similar to FIG. 1 but with additional broken lines;

FIG. 10 is a view similar to FIG. 1 but with additional broken lines;

FIG. 11 is a perspective view of the card reader showing our new design in a second orientation;

FIG. 12 is another perspective view thereof;

FIG. 13 is a top plan view thereof;

FIG. 14 is a bottom plan view thereof;

FIG. 15 is front elevational view thereof;

FIG. 16 is a rear elevational view thereof;

FIG. 17 is a left side elevational view thereof;

FIG. 18 is a right side elevational view thereof;

FIG. 19 is a view similar to FIG. 11 but with additional broken lines;

FIG. 20 is a view similar to FIG. 11 but with additional broken lines;

FIG. 21 is a perspective view of the card reader showing our new design in a third orientation;

FIG. 22 is another perspective view thereof;

FIG. 23 is a top plan view thereof;

FIG. 24 is a bottom plan view thereof;

FIG. 25 is front elevational view thereof;

FIG. 26 is a rear elevational view thereof;

FIG. 27 is a left side elevational view thereof;

FIG. 28 is a right side elevational view thereof;

FIG. 29 is a view similar to FIG. 21 but with additional broken lines;

(Continued)

FIG. 30 is a view similar to FIG. 21 but with additional broken lines;

FIG. 31 is a perspective view of the card reader showing our new design in a fourth orientation;

FIG. 32 is another perspective view thereof;

FIG. 33 is a top plan view thereof;

FIG. 34 is a bottom plan view thereof;

FIG. 35 is front elevational view thereof;

FIG. 36 is a rear elevational view thereof;

FIG. 37 is a left side elevational view thereof;

FIG. 38 is a right side elevational view thereof;

FIG. 39 is a view similar to FIG. 31 but with additional broken lines; and,

FIG. 40 is a view similar to FIG. 31 but with additional broken lines.

The broken lines in each of FIGS. 1-3, 5, 6, 11-13, 15, 16, 21-23, 25, 26, 31-33, 35, and 36 show portions of the card reader that form no part of the claimed design.

The broken lines in each of FIGS. 9, 10, 19, 20, 29, 30, 39, and 40 show portions of the card reader that form no part of the claimed design, and also show a card that is environmental structure and forms no part of the claimed design.

The multiple orientations shown in the drawings are achieved by rotating/swiveling the top two-thirds of the card reader relative to the bottom one-third, in 90° increments. The transition between the orientations shown in the drawings forms no part of the claimed design.
